CAP FEEDING DEVICE

William J. Mundy, University City, Mo., assignor
to C. T. Small Manufacturing Company, St.
Louis, Mo., a corporation of Missouri

Application January 2, 1936, Serial No. 57,174

10 Claims. (Cl. 113—114)

My invention relates to cap feeding devices and more particularly to such devices as are used to feed properly caps to can capping machines.

5 Usually, the caps fed to and used by capping machines have a top and a bottom of different surface contours. That is, the bottom usually has an external or internal flange adapted to engage the outer or inner side, respectively, of the 10 end of a can. In some cases the top of a cap is flat, but in other cases, particularly, where an internal flange is provided, the top of a cap has a surface contour which is the reverse of that of the bottom.

15 The caps to be fed usually are dumped into a hopper or bin from which they are expelled by some suitable expedient in a row along a track. Of course, some of the caps are in rows right side up, that is, positioned to be fed directly to 20 the capping machine and others are wrong side up and must be inverted before being fed to the machine. Although, heretofore, several different devices have been made to position properly the caps on the track or conveyor along which they 25 move to the capping machine, such expedients have been inefficient and could not be relied upon to accomplish the desired result. If the caps are put on the track by hand the cost of operation of the capping machine is increased greatly 30

30 by this additional labor. Therefore, the object of my invention is to provide a cap feeding device which will positively and automatically assure that all caps delivered therefrom to the capping machine will be in proper relative position.

35 One embodiment of a device for accomplishing the above object in a manner contemplated by my invention, is shown fully in the accompanying drawings wherein similar characters are 40 used to designate similar parts: In these drawings, Fig. 1 is a top view of the device; Fig. 2 is an elevation, partly in section, along the lines 2—2 in Fig. 1; Fig. 3 is a transverse section along the lines 3—3 in Fig. 2; Fig. 4 is a side elevation 45 of the machine; Fig. 5 is a section of the device as indicated by the line 5—5 in Fig. 1; Fig. 6 is a view similar to that of Fig. 5, but with some of the parts in different positions from that shown in the other figure; and Figs. 7 and 8 show details 50 of construction as explained hereinafter.

55 Referring to the figures the embodiment shown therein is adapted to feed caps having a top formed in a plane surface and a bottom having an annular depending flange to engage the outer marginal surface of a can. These caps must be

fed, of course, with the plane surface up and the flanged surface down so that the capping machine may place them on the can without changing their position. The device illustrated has a compartment with a circular, upstanding side wall 1 and a bottom wall formed by a rotatable plate 2. These and other parts of the device are supported on a frame including a foot 3 and vertical rods 4. The side wall 1 is directly mounted on bracket arms 5 extending from the rods 4. The rotatable shaft 6, carrying the plate 2, is mounted in an upper bearing supported by the cross arms 7 extending between the rods 4 and by a boss 8 formed in the foot 3. Extending inwardly from and supported by the annular side wall 1 is a partition 9 arranged to divide the compartment into a bin into which are dumped caps to be fed and a space in which is mounted various parts of the feeding device, as described below.

55 Arranged at the outer peripheral edge of the rotatable plate 2 is a rotating brush 10 fixed to a shaft 11 carried by the bracket 12. Leading from the brush at the side thereof away from the bin is a primary track, indicated at 13. This track 25 is formed, in this embodiment, by the inner side of the circular wall, side rails 14 and 15, arranged generally to follow the contour of the wall 1, and by an arcuate shaped top guide strip 16 to prevent the caps from being thrown upwardly away from contact with the side rails. The bottom of the track is formed by the plate 2. The rails 14 and 15 are maintained in place by fingers 17 extending from the wall 1 and the top 30 guide strip 16 is carried by angles 18, also carried by the annular wall. It will be evident that when the plate is rotated in the direction indicated by the arrow in Fig. 1, caps in the bin will be carried to the rotating brush 10 and will be moved in a row into and along the track 13. 40 Preferably, a guide strip 19 is arranged to guide the caps in the bin into contact with the brush 10. A conveyor 21 is arranged to extend from the track 13 as a continuation thereof and to carry the caps from the feeding device to a capping machine, not shown.

45 Adjacent a portion of the primary track 13 is an auxiliary track 20 which, in this embodiment, is formed by the rail 15 and the partition 9 which are arranged for this purpose. The auxiliary track 20 has a top guide strip 16^a and its bottom is formed by the plate 2.

50 Obviously, as the caps move into the track 13 some will be correctly positioned with the top up and others will be incorrectly positioned with the 55

top down. In this embodiment of my invention the caps which are correctly positioned will move through the track 13 and out on the conveyor 21, but the caps which are incorrectly positioned 5 will be taken out of the row of caps on the track 13 and moved onto the auxiliary track 20.

To accomplish this result I provide a selector 10 mounted at the junction of the primary track 13 and the auxiliary track 20. This selector, as shown in detail in Figs. 5 and 6, comprises a disc 22 mounted on a ball bearing 23 carried at the lower end of a stub shaft 24 which, in turn, 15 is carried by a bar 25 fixed to the side wall 1. Preferably, the upper end of the shaft 24 is positioned in a slot 25a whereby the adjustment of the stub shaft 24 and its carried disc 22 may be changed relative to the track along which the caps move. To adjust the selector a lock nut 26 at the upper end of the shaft is loosened and 20 the shaft is moved in the slot 25a into a desired adjusted position and then the lock nut 26 is tightened to hold the parts in such adjusted position.

The disc 22 has formed in its outer periphery 25 a plurality of arcuate shaped recesses 27, each arranged to receive a portion of the side of a cap. As the caps move along the track 13 they will be engaged in a recess 27 and will rotate the disc in the direction indicated in Fig. 1. 30 Carried on the disc 22 are a plurality of fingers 28 arranged so that each one extends outwardly from the disc substantially centrally of a recess 27. In the embodiment shown the fingers 28 are in the shape of a bell crank and are pivotally 35 mounted at their elbows on blocks 29. Springs 30 are arranged between the hub 31 of the disc and the upwardly extending part of each finger whereby the lower part of each finger normally 40 will project horizontally outwardly from the disc in a recess 27. Each of the outwardly extending parts of the fingers 28 are notched as indicated at 32 and have an upwardly inclined edge leading outwardly from said notch, as shown.

A cam strip 33 is positioned to engage the 45 upwardly extending parts of the fingers as they move around with the disc and thereby move the fingers to carry the lower part thereof upwardly, all as shown in Fig. 8.

The operation of the selector described above, 50 is as follows: As the caps move along the track 13 they will be engaged successively in one of the recesses 27 of the disc 22 and thereby will rotate the disc. As the disc rotates the upwardly inclined lower edge of a finger 28 associated with a recess engaging a cap will slide along the upper corner edge of the cap so engaged and the spring 30 will be compressed to allow the finger to move into the position shown in Fig. 5. If the cap is correctly positioned with 55 the plane surface upwardly the finger will be supported in this position until the cap has moved along the track 13 out of engagement with the recess. However, if the cap is upside down the lower part of the finger will not be so supported but will be moved downwardly by action of its spring to bring the notch 32 into engagement with the flange on the lower side of the cap. As the disc is rotated by other caps being engaged by other recesses in the 60 disc the cap which is upside down will not be allowed to move on in the row along the track 13, but will be carried by the finger out of the row and into a position at the upper end of the auxiliary track 20. When the cap has been carried into this position the cam 33 acting on the 65

finger 28, as described above, will move the finger to release the cap and the cap will be moved along the auxiliary track by rotation of the plate 2.

In the embodiment shown caps from the auxiliary track 20 are delivered to an inverting apparatus consisting of a rotating drum 34 and a flexible strap 35 associated therewith. Normally, the strap 35 is impelled into contact with the outer periphery of the drum 34 by a spring 36. As a cap moves from the auxiliary track 20 it will be carried around the drum 34 inside of the strap 35 and when delivered from the drum at the top thereof the cap will be in proper position. The caps so delivered are 15 moved onto a conveyor 37 which, in this embodiment, discharges the properly positioned caps back into the bin. However, I contemplate that the feeding device as disclosed herein may be used with two capping machines, with one 20 of the capping machines being fed from the conveyor 21 of the primary track 13 and the other being fed from the conveyor 37.

The various parts of a device embodying my 25 invention may be driven by any suitable expedients, but in the embodiment shown and described herein a power applied to a driving shaft 38, as shown in Fig. 2, will be transmitted through beveled gears 39 and a chain drive 40 to rotate the shaft 6 carrying the plate 2. Similarly, this 30 power through gears 41 and shaft 42 may be transmitted through the chain drives 43 and 44 to the drum 34 and the shaft 11 of the brush 10, respectively.

The disc 22 in addition to comprising a part 35 of the selector also will act, in the form shown, as the spacer for the caps moving along the conveyor 21 to the capping machine. Since the disc 22 is not rotated by any force except movement of the caps along the track 13, if the 40 capping machine is stopped or if it does not take caps from the row in the conveyor 21 the rotation of the disc 22 will stop movement of the caps until a cap is taken from the conveyor 21 to allow the row to move forwardly.

Obviously, I do not intend to limit my invention to the particular embodiment shown in the drawings nor do I intend to limit it for use only with the form of cap shown. The size, shape and arrangement of the parts and the expedients used 50 for moving the caps along the tracks and for feeding them into the tracks may be varied within wide limits without deviating from the spirit of my invention. In adapting my invention to devices for feeding caps of shapes other than that 55 shown it may be necessary to change the shape and size of the disc 22 and fingers 28, but, as stated above, I contemplate such changes as long as they come within the ambit of the claims included below.

What I claim as new and desire to secure by Letters Patent, is:

1. In a device for feeding caps having a top and a bottom with different surface contours, a track for a row of caps, means for moving said caps along said track, a pivotally mounted finger arranged to be moved in cycles progressively over and away from said track, said finger being arranged and positioned whereby when it is moved over said track it will pivot to engage firmly a 65 cap presenting a certain predetermined surface contour and movement of said finger away from said track will carry said cap out of said row but when said finger contacts a cap not presenting said predetermined contour said finger will 70 75

slide over said cap without pivoting and will not engage therewith.

2. In a device for feeding caps having a top and a bottom with different surface contours, a track for a row of caps, means for moving said caps along said track, a pivotally mounted finger arranged to be moved in cycles progressively over and away from said track, said finger being arranged and positioned whereby when it is moved over said track it will pivot downwardly to engage firmly a cap presenting a certain predetermined surface contour and movement of said finger away from said track will carry said cap out of said row but when said finger contacts a cap not presenting said predetermined contour said finger will slide over said cap and will not move downwardly to engage therewith.

3. In a device for feeding caps having a top and a bottom with different surface contours, a track for a row of caps, means for moving said caps along said track, a pivotally mounted finger arranged to be moved in cycles progressively over and away from said track, said finger being arranged and positioned whereby when it is moved over said track it will pivot to engage firmly a cap presenting a certain predetermined surface contour and movement of said finger away from said track will carry said cap out of said row but when said finger contacts a cap not presenting said predetermined contour said finger will slide over said cap without pivoting and will not engage therewith, and means associated with said finger for moving said finger out of engagement with said predetermined contour on a cap when it has been carried out of said row.

4. In a device for feeding caps having a top and a bottom with different surface contours, a track for a row of caps, means for moving said caps along said track, a pivotally mounted finger arranged to be moved in cycles progressively over and away from said track, said finger being arranged and positioned whereby when it is moved over said track it will pivot downwardly to engage firmly a cap presenting a certain predetermined surface contour and movement of said finger away from said track will carry said cap out of said row but when said finger contacts a cap not presenting said predetermined contour said finger will slide over said cap and will not move downwardly to engage therewith, and means associated with said finger for moving said finger upwardly away from a cap and out of engagement therewith when the cap has been carried out of said row.

5. In a device for feeding caps having a top and a bottom formed with a peripherally extending flange, a track for a row of said caps, means for moving said caps along said track, a pivoted finger having a notch therein and mounted and arranged to be moved in cycles progressively over and away from said track, said finger being arranged and positioned whereby when it is moved over said track the notch therein will engage the flange on a cap if said cap is positioned to present said flange to said finger, and movement of said finger away from said track will carry said cap out of said row, but said finger will slide over and will not engage a cap not positioned to present a flange to said finger and the cap will not be carried out of said row.

6. In a device for feeding caps having a top and a bottom formed with a peripherally extending flange, a track for a row of said caps, means for moving said caps along said track, a pivoted finger having a notch therein and mounted and

arranged to be moved in cycles progressively over and away from said track, said finger being arranged and positioned whereby when it is moved over said track the notch therein will engage the flange on a cap if said cap is positioned to present said flange to said finger, and movement of said finger away from said track will carry said cap out of said row, but said finger will slide over and will not engage a cap not positioned to present a flange to said finger and the cap will not be carried out of said row, and means associated with said finger for pivoting said finger to release the flange from said notch when a cap has been carried out of said row.

7. In a device for feeding caps having a top and a bottom with different surface contours, a primary track for a row of caps, means for moving said caps along said primary track, an auxiliary track leading from said primary track, a freely rotatable selector mounted at the junction of said primary and auxiliary tracks, said selector comprising a disc having a plurality of recesses formed and adapted to receive a portion of the edge of one of said caps on said primary tracks whereby when said caps move along said track each will be engaged successively in one of the recesses on said selector and said selector will be rotated by movement of said caps, a plurality of fingers each having a notch therein and carried by said rotatable disc and positioned so that one of said fingers extends outwardly in each of said recesses whereby when said selector is rotated said fingers will move in cycles progressively over and away from said primary track and each of said fingers being positioned and arranged so that as it moves across said primary track it will engage firmly a cap having a predetermined surface contour and as said finger moves away from said primary track it will carry the cap so engaged off of said primary track and onto said auxiliary track.

8. In a device for feeding caps having a top and a bottom with different surface contours, a primary track for a row of caps, means for moving said caps along said primary track, an auxiliary track leading from said primary track, a freely rotatable selector mounted at the junction of said primary and auxiliary tracks, said selector comprising a disc having a plurality of recesses formed in the peripheral edge thereof with each of said recesses formed and adapted to receive a portion of the edge of one of said caps on said primary track whereby when said caps move along said track each will be engaged successively in one of the recesses on said selector and said selector will be rotated by movement of said caps, a plurality of fingers each having a notch therein and carried by said rotatable disc and positioned so that one of said fingers extends outwardly in each of said recesses whereby when said selector is rotated said fingers will move in cycles progressively over and away from said primary track, each of said fingers being positioned and arranged so that as it moves across said primary track it will engage firmly a cap having a predetermined surface contour and as said finger moves away from said primary track it will carry the cap so engaged off of said primary track and onto said auxiliary track, and means to disengage said fingers from said caps carried onto said auxiliary track.

9. In a device for feeding caps having a top and a bottom with different surface contours, a primary track for a row of caps, means for moving said caps along said primary track, an aux-

iliary track leading from said primary track, a freely rotatable selector comprising a disc having a plurality of recesses each formed and adapted to receive a portion of the edge of one of said caps on said primary track, said selector being positioned relative to said primary track so that as said caps move along said track each will be engaged successively in one of said recesses and said selector will be rotated by movement of said caps, a plurality of pivotally mounted fingers carried by said rotatable disc and positioned so that one of said fingers extends outwardly in each of said recesses whereby when said selector is rotated said fingers will move in cycles progressively over and away from said primary track, each of said fingers being positioned and arranged so that as it moves across said primary track it will pivot to engage firmly a cap presenting a certain predetermined surface contour, and as said finger moves away from said primary track said finger will carry said cap off of said primary track onto said auxiliary track, but when said finger contacts a cap not presenting said predetermined contour said finger will slide over said cap without pivoting and will not engage therewith.

10. In a device for feeding caps having a top and bottom formed with a peripherally extending flange, a primary track for a row of said caps,

means for moving said caps along said primary track, an auxiliary track leading from said primary track, a freely rotatable selector comprising a disc having a plurality of recesses formed in the peripheral edge thereof with each of said recesses formed and adapted to receive a portion of the edge of one of said caps on said primary track, said selector being arranged relative to said primary track whereby when said caps move along said track each will be engaged successively in one of said recesses and said selector will be rotated by movement of said caps, a plurality of fingers each having a notch therein carried by said rotatable disc and positioned so that one of said fingers extends outwardly in each of said recesses whereby when said selector is rotated said fingers will move in cycles progressively over and away from said primary track, each of said fingers being positioned and arranged so that as it moves over said primary track the notch therein will engage the flange on a cap if said cap is positioned to present said flange to said finger, and as said finger moves away from said track said finger will carry said cap from said primary track onto said auxiliary track, but said finger will slide over and will not engage a cap not positioned to present a flange to said finger and the cap will not be carried out of said row.

WILLIAM J. MUNDY.

CERTIFICATE OF CORRECTION.

October 17, 1939.

Patent No. 2,176,659.

WILLIAM J. MUNDY.

It is hereby certified that error appears in the printed specification of the above numbered patent requiring correction as follows: Page 3, first column, line 57, claim 5, for the word "stack" read track; and second column, line 25, claim 7, for "tracks" read track; page 4, first column, line 14, and second column, line 17, claims 9 and 10 respectively, for "fingers" read finger; same page, first column, line 29, claim 10, for "primry" read primary; and that the said Letters Patent should be read with this correction therein that the same may conform to the record of the case in the Patent Office.
